OIL WELL JAR

Clifford M. Howard, Fontana, Calif.

Application February 27, 1951, Serial No. 212,977

9 Claims. (Cl. 255—27)

1

This invention relates to an oil well jar of the longitudinally striking type, that is, one in which a longitudinal movement is imparted to the tool causing a latch means to be released and permitting a hammer to strike against an anvil, thus striking a blow against the body of the tool which is attached to the lost or stuck pipe.

An object of my invention is to provide a novel oil well jar in which a collet is employed to engage a tapered shoulder, the collet compressing under tension to permit the mandrel to release and cause the hammer to strike the anvil.

Another object of my invention is to provide a novel means of eliminating the back-lash in the tool due to a required looseness in the spline construction of the tool.

Still another object of my invention is to provide a novel means of wedging the collet against its shoulder by means of a spring pressed wedge ring, the tension of the spring being variable to vary the longitudinal pull necessary to operate the tool.

A feature of my invention is to provide a novel finger ring construction in which tapered fingers are wedged into the spline construction of the tool to eliminate back-lash.

Other objects, advantages and features of invention may appear from the accompanying drawing, the subjoined detailed description and the appended claims.

In the drawing:

Figure 1 is a partial longitudinal sectional view of my tool in collapsed position.

Figure 2 is a partial longitudinal sectional view of my tool in extended position.

Figure 3 is a sectional view taken on line 3—3 of Figure 1.

Figure 4 is a sectional view taken on line 4—4 of Figure 1.

Figure 5 is a fragmentary longitudinal sectional view showing the finger ring and collet construction.

Referring more particularly to the drawing, the numeral 1 indicates a tubular body which may be formed in two parts 2—3, which are threaded together as shown at 4. A mandrel 5 extends into the body 1 and is longitudinally movable within the body, as will be further described. A packing nut 6 screws into the top of the body 1 and compresses the packing 7 around the mandrel 5 to prevent fluid leakage.

An anvil ring or nut 8 is threaded into the upper part of the portion 2 of the body and is arranged below the packing 7, substantially as shown. This anvil projects inwardly a slight dis-

2

tance, as shown, so as to provide a shoulder against which the mandrel shoulder 9 strikes. A coupling 10 on the upper end of the mandrel permits this mandrel to be threaded on to the drill pipe upon which the tool is run. The lower part 3 of the body 1 is formed with a threaded pin 11 which screws into the lost tool or pipe or whatever the jar might be run on.

The lower end of the mandrel 5 is formed with a plurality of spaced vertical slots 12 into which the spines 13 on the body 1 extend. In order that the mandrel 5 may drop freely, it is necessary that spines 13 will fit rather loosely in the slots 12 of the mandrel. This would normally cause a certain amount of looseness or back-lash and I overcome this looseness in the following manner:

A finger ring 14 is mounted in the lower portion 3 of the body 1, as best shown in Figure 5. The finger ring 14 includes a base 15 from which springs 16 extend to engage the ring 14 and press this ring upwardly. The lower end of the finger 17 of the mandrel 5 is tapered, as shown at 18, and the tapered fingers 14 fit against the taper 18 on the one side and against the spines 13 on the other, thus wedging between the spines and the fingers 17, which takes out the looseness or play between the spines 13 and the fingers 17, thereby eliminating back-lash.

The base 15 rests on a shoulder 19 in its lower position and the ring is prevented from moving upwardly by the pins 20 which project horizontally from the fingers 14 and engage the lower edge of the spines 13, thus eliminating the upward movement of the finger ring.

A collet 21 is tubular in form and is cut lengthwise to form spring fingers, substantially as shown. The upper end of the collet screws into the lower end of the mandrel 5, as shown at 22. Its lower end is provided with tapered shoulders 23 which engage the lower tapered edge of a ring 24 in the body portion 3. The collet 21 is spread outwardly to engage the ring 24 by means of a wedge ring 25 which is pressed upwardly by the coil spring 26. The spring 26 rests on a nut 27 which screws into the body portion 3 adjacent its lower end and can be threaded upwardly or downwardly to vary the tension of the spring 26, as may be necessary. The spring 26 presses the wedge ring 25 upwardly with varying pressure, thus expanding the collet 21 and causing the tapered shoulders 23 to press against the ring 24 so that a considerable force is required before the mandrel 5 can be pulled upwardly in the body 1. When the collet 21 escapes the ring

24 it will move upwardly permitting the hammer 9 to strike the anvil 8 and causing an upward jar or blow on the body 1.

Normally, the oil well jar is held in collapsed position by the shear pins 28 and this collapsed position is maintained during normal drilling operations. In the collapsed position the finger ring 14 is in the position shown in Figure 5 and backlash is taken out of the tool. When it is desired to jar to remove drill pipe which might be stuck or other tool attached to the jar, then the shear pins 28 are sheared and the tool is used as a longitudinally striking jar.

Having described my invention, I claim:

1. An oil well jar comprising a tubular body, coupling means on the lower end of said body, a mandrel extending into said body and slidable vertically therein, coupling means on the upper end of said mandrel, a shoulder in said body forming an anvil, a second shoulder on the mandrel forming a hammer and engageable with the anvil, a latch ring in said body, releasable means on the mandrel engaging said latch ring, splines on the inside of said body, said mandrel having grooves therein to receive the splines, said grooves forming fingers therebetween in the mandrel, a finger ring mounted in said body, projecting fingers on said finger ring, said projecting fingers engaging the first named fingers to take up looseness between the first named fingers and the splines.

2. An oil well jar comprising a tubular body, coupling means on the lower end of said body, a mandrel extending into said body and slidable vertically therein, coupling means on the upper end of said mandrel, a shoulder in said body forming an anvil, a second shoulder on the mandrel forming a hammer and engageable with the anvil, a latch ring in said body, releasable means on the mandrel engaging said latch ring, splines on the inside of said body, said mandrel having grooves therein to receive the splines, said grooves forming fingers therebetween in the mandrel, a finger ring mounted in said body, projecting fingers on said finger ring, said projecting fingers engaging the first named fingers to take up looseness between the first named fingers and the splines, and spring means pressing the finger ring into engagement with the first named fingers.

3. An oil well jar comprising a tubular body, coupling means on the lower end of said body, a mandrel extending into said body and slidable vertically therein, coupling means on the upper end of said mandrel, a shoulder in said body forming an anvil, a second shoulder on the mandrel forming a hammer and engageable with the anvil, a latch ring in said body, releasable means on the mandrel engaging said latch ring, splines on the inside of said body, said mandrel having grooves therein to receive the splines, said grooves forming fingers therebetween in the mandrel, a finger ring mounted in said body, projecting fingers on said finger ring, said projecting fingers engaging the first named fingers to take up looseness between the first named fingers and the splines, and spring means pressing the finger ring into engagement with the first named fingers, a shoulder in the body on which the finger ring rests, and pins projecting from the last named fingers and engageable with said splines to eliminate upward movement of the finger ring.

4. An oil well jar comprising a tubular body, coupling means on the lower end of said body, a mandrel extending into said body and slidable vertically therein, coupling means on the upper end of said mandrel, a shoulder in said body form-

ing an anvil, a second shoulder on the mandrel forming a hammer and engageable with the anvil, a collet depending from said mandrel, a shoulder on the inside of the body engageable by said collet, said collet being releasable from said shoulder on upward movement of the mandrel, splines on the inside of said body, said mandrel having grooves therein to receive the splines, said grooves forming fingers therebetween in the mandrel, a finger ring mounted in said body, projecting fingers on said finger ring, said projecting fingers engaging the first named fingers to take up looseness between the first named fingers and the splines.

5. An oil well jar comprising a tubular body, coupling means on the lower end of said body, a mandrel extending into said body and slidable vertically therein, coupling means on the upper end of said mandrel, a shoulder in said body forming an anvil, a second shoulder on the mandrel forming a hammer and engageable with the anvil, a collet depending from said mandrel, a shoulder on the inside of the body engageable by said collet, said collet being releasable from said shoulder on upward movement of the mandrel, a wedge ring engageable with the collet, and spring means pressing said wedge ring upwardly against the bottom of the collet, splines on the inside of said body, said mandrel having grooves therein to receive the splines, said grooves forming fingers therebetween in the mandrel, a finger ring mounted in said body, projecting fingers on said finger ring, said projecting fingers engaging the first named fingers to take up looseness between the first named fingers and the splines.

6. An oil well jar comprising a tubular body, coupling means on the lower end of said body, a mandrel extending to said body and slidable vertically therein, coupling means on the upper end of said mandrel, a shoulder on the inside of the body forming an anvil, a second shoulder on the mandrel forming a hammer, said hammer being engageable with the anvil, splines on the inside of the body, said mandrel having vertical slots therein to receive the splines, said slots forming fingers in the mandrel therebetween, the lower ends of said fingers being tapered, a finger ring mounted in the body below the mandrel, upwardly projecting fingers on the finger ring, the last named fingers engaging the tapered faces of the first named fingers, and the splines to prevent back-lash in the mandrel, a collet depending from the mandrel, a latch shoulder in the body engageable by the collet, said collet being releasable from the last named shoulder on upward pull of the mandrel.

7. An oil well jar comprising a tubular body, coupling means on the lower end of said body, a mandrel extending to said body and slidable vertically therein, coupling means on the upper end of said mandrel, a shoulder on the inside of the body forming an anvil, a second shoulder on the mandrel forming a hammer, said hammer being engageable with the anvil, splines on the inside of the body, said mandrel having vertical slots therein to receive the splines, said slots forming fingers in the mandrel therebetween, the lower ends of said fingers being tapered, a finger ring mounted in the body below the mandrel, upwardly projecting fingers on the finger ring, the last named fingers engaging the tapered faces of the first named fingers and the splines to prevent back-lash in the mandrel, a collet depending from the mandrel, a latch shoulder in the body engage-

able by the collet, said collet being releasable from the last named shoulder on upward pull of the mandrel, a wedge ring engaging the lower end of the collet and spreading the collet into the last named shoulder, and spring means pressing the wedge ring against the collet.

8. An oil well jar comprising a tubular body, coupling means on the lower end of said body, a mandrel extending into said body and slidably vertically therein, coupling means on the upper end of said mandrel, a shoulder on the inside of the body forming an anvil, a second shoulder on the mandrel forming a hammer, said hammer being engageable with the anvil, splines on the inside of the body, said mandrel having vertical slots therein to receive the splines, said slots forming fingers in the mandrel therebetween, the lower ends of said fingers being tapered, a finger ring mounted in the body below the mandrel, upwardly projecting fingers on the finger ring, the last named fingers engaging the tapered faces of the first named fingers and the splines to prevent back-lash in the mandrel, spring means engaging the finger ring and pressing said finger ring into engagement with said fingers on the mandrel, a collet depending from the mandrel, a latch shoulder in the body engageable by the collet, said collet being releasable from the last named shoulder on upward pull of the mandrel.

9. An oil well jar comprising a tubular body, coupling means on the lower end of said body, a mandrel extending into said body and slidably vertically therein, coupling means on the upper

end of said mandrel, a shoulder on the inside of the body forming an anvil, a second shoulder on the mandrel forming a hammer, said hammer being engageable with the anvil, splines on the inside of the body, said mandrel having vertical slots therein to receive the splines, said slots forming fingers in the mandrel therebetween, the lower ends of said fingers being tapered, a finger ring mounted in the body below the mandrel, upwardly projecting fingers on the finger ring, the last named fingers engaging the tapered faces of the first named fingers and the splines to prevent back-lash in the mandrel, spring means engaging the finger ring and pressing said finger ring into engagement with said fingers on the mandrel, a collet depending from the mandrel, a latch shoulder in the body engageable by the collet, said collet being releasable from the last named shoulder on upward pull of the mandrel, a wedge ring engaging the lower end of the collet and spreading the collet into the last named shoulder and spring means pressing the wedge ring against the collet.
